UNITED STATES PATENT OFFICE.

FREDERICK EISSNER, OF NEW YORK, N. Y.

THERMOMETER.

SPECIFICATION forming part of Letters Patent No. 320,119, dated June 16, 1885.

Application filed February 11, 1885. (No model.)

To all whom it may concern:

Be it known that I, FREDERICK EISSNER, of the city, county, and State of New York, have invented a new and useful Improvement 5 in Thermometers; and I do hereby declare that the following is a full and exact description thereof, reference being had to the accompanying drawings, and to the letters of reference marked thereon, making a part of this specification.

My invention relates to an improvement in self-registering fever-thermometers.

As heretofore constructed these thermometers have been made similar to ordinary thermometers, with the exception that a small index-column is separated by an air-bubble from the upper end of the main column of mercury in the tube. In this simple form the index-column is liable to drop into the tube and be lost. A remedy has been sought for this difficulty by drawing out the end of the mercury-bulb into a slender tube, which is bent up above the bulb in a flat S or loop shaped portion, or by bending the lower end of the 20 graduated mercury-tube above the bulb into a double or S-shaped bend, the bent portion of the tube being protected by an exterior tube or casing.

The object of my invention is to prevent the loss of the index-column without bending the mercury-tube, and to thereby simplify the construction of a reliable self-registering thermometer in which the registering device is unalterable. This I have accomplished by constructing 35 a thermometer with a sealed mercury-tube containing a column of mercury separated by an air-bubble, and whose lower open end is made to project into an encircling sealed bulb closely to the bottom of the bulb, whereby said lower 40 end will remain constantly covered and surrounded by the mercury in the bulb. By this means the air-bubble confined below the upper index-division of the divided column of mercury is absolutely prevented from passing into 45 the bulb, and is positively confined, so that it may not be lost, thus rendering the registering device indestructible so long as the instrument remains intact, while it permits, also, the construction of the thermometer in the straight, 50 slender, cylindrical form of uniform diameter which is most convenient and useful.

In the accompanying drawings, Figure 1 is an elevation of my improved registering-thermometer when constructed in form for a physician's use, and Fig. 2 a longitudinal central 55 section thereof.

A represents the glass tube ordinarily employed in thermometers, provided with a suitable scale upon its face, as shown in Fig. 1. The lower end, a, of this tube is reduced in 60 diameter, and the bulb B is made to encircle this smaller end of the tube, so that the tube shall project down into the bulb and open into it near to the bottom thereof, as shown in Fig. 2.

The concentric space between the wall of the 65 bulb and the lower end of the tube projecting into the same is made large enough to contain the proper charge of mercury, and in filling the bulb and tube, which is done in the customary manner well known to the art, a small 70 portion, c, of the mercury is separated from the main body of the column in the tube by means of an interposed air space or bubble, D, which, when the thermometer is sealed, is absolutely confined in the column, so as to separate 75 constantly the small registering-division c of mercury from the remainder thereof. This small body c of mercury, separated from the rest at the top of the column by the intervening confined air-bubble D, will be carried 80 up when the mercury rises in the tube, but will, by reason of its attraction and frictional adhesion to the sides of the tube, remain at the extreme upper point to which it may be thus carried, when the main column drops 85 again into the bulb, and thus remaining stationary will serve as an accurate register of the extreme height to which the mercury has ascended.

The registering-division c may be made to 90 drop back to the bulb, when required, by slight percussion; but the air-bubble D cannot be driven out of the tube, because of the fact that its lower end is constantly immersed in mercury, insuring a continued pressure thereon, 95 even when the column in the tube drops so low as that the air-bubble D is brought to its extreme lower end.

I am aware that "manometers" have been constructed with a bulb encircling the lower 100 end of an index-tube, which is open at the top, the bulb being either enlarged and extended

(No Model.)
